(57) **CLAIM**

The ornamental design for a hockey training apparatus, as shown and described.

DESCRIPTION

FIG. 1 is a front-top perspective view of a hockey training apparatus showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a rear-bottom perspective view thereof.

1 Claim, 7 Drawing Sheets
